UNITED STATES PATENT OFFICE.

CLAYTON A. PETERSON, OF ROCHESTER, NEW HAMPSHIRE, ASSIGNOR TO SPAULDING FIBRE COMPANY, INC., OF NORTH ROCHESTER, NEW HAMPSHIRE, A CORPORATION OF NEW HAMPSHIRE.

METHOD OF MAKING COUNTERS.

Application filed July 26, 1926. Serial No. 125,004.

This invention relates to the method of making moulded counters for boots and shoes of the type having a forward wing at the inner side, at least, which overlaps, to a greater or less degree, the contour of the last at its inside shank or at the instep of the foot of the wearer of the shoe.

Heretofore counters of the type described have been assembled with the sole and upper materials on the last while in the condition as delivered from the usual counter-moulding machine, that is, with no definite shaping of the forward wing in a manner to fit the inside shank portion of the last which this extension overlaps. This forwardly extending wing, in the form of the counter coming from the counter-moulding machine may have been merely rolled leaving it substantially flat with a long straight edge running forward from the heel-seat flange. An incompletely moulded wing is an unfinished product and requires conformation to the shape of the last while the upper is being lasted, a most difficult operation owing to the stiffness of the counter material, with the result that there is no certainty that even the two shoes of the same pair will look or feel alike throughout the instep, after completion. This is not fine shoemaking.

By practising the method of the present invention the shoemaker is assured that all wing counters for any size or style will, without further conformation by lasting, accurately fit the inside shank of the last for that size or style at the time of assembly. This means that the style of the shoe, as meant to be determined by the design of the last, will be preserved and perpetuated when the shoemaking process is completed. This perfection of the shoemaking process has been much desired and long sought but its full effect in quantity production has never been attained until this invention was conceived and practised.

The object of the present invention is to improve the manufacture of counters in such manner as to eliminate the necessity of shaping the counter to the last during the lasting operation thereby overcoming the defects in the completed shoe due to an improper moulding, shaping or positioning of the counter, or a portion thereof.

To the accomplishment of this object the invention consists in the method of making

counters, the preferred manner of practising which is hereinafter described and defined in the appended claims.

An understanding of the invention will be assisted by reference to the accompanying drawing, in which:

Figure 1 is a view, in perspective, of lower and upper male and female moulds respectively, for moulding the forward wings of counters of the type hereinbefore described. These two moulds are shown in open relation as mounted in any suitable type of moulding press;

Fig. 2 is a front end view of the lower mould;

Fig. 3 is a view, in side elevation, of the lower mould viewed from the heel-seat side, having an incompletely moulded wing counter seated thereon in position for receiving pressure on its wing from the upper mould;

Fig. 4 is a view, in transverse section, through the instep portion of the lower mould, illustrating a counter wing thereabove before being moulded.

Fig. 5 is a view, in section, similar to Fig. 3, illustrating the two moulds in moulding relation upon an interposed counter wing; and

Figs. 6 and 7 are views, in perspective, of two types of wing counters that have been prepared for use in a shoe by the method of this invention.

In making the counter a rolled and crimped, or "clam-shell", counter blank is prepared by the usual processes. This blank is then introduced to a counter-moulding machine of any approved type but which, preferably, may be the type of machine disclosed in Letters Patent of the United States to R. A. Lancey, No. 1,138,123, dated May 4, 1915. This machine operates to bend and press the blank, while in temper, over an inner mould block shaped like the heel end of the last for the particular size and style of the shoe in which the counter is to be used and presenting its heel end uppermost, and thereafter the lower margin of the moulded blank is wiped inward to produce a heel-seat flange. The blank being operated upon, it should be understood, is of the type having a forwardly extending wing at its inner side, but this wing may not be acted upon by either the heel end moulds or the wiper of the counter-moulding machine, i. e. after

the moulding step just described the wing may still be merely in its rolled state with a substantially straight lower edge. The moulds do not produce a wing having the form and shape of the instep portion of the last. Prior to this invention quantity production of wing counters in any other form than with an incompletely moulded wing could not be obtained, with the result that the last must attempt to unbuckle the forward wing and draw it snugly to the contour of the instep portion of the last while he is lasting the upper. In this but little success was attained and the wing counter, although highly desirable, has heretofore been little used in the manufacture of fine shoes.

By practising the method of the present invention the moulding of wing counters is successfully and accurately accomplished, with the result that this highly important adjunct of fine shoemaking is now available in such a form that its use materially aids instead of detracts from the style trim of fine shoes.

In completing the counter-moulding process the partially moulded wing counter is preferably, but not necessarily, placed in a second counter-moulding machine having a lower, male mould block 10 the surface of which is shaped like the heel and instep portions of the last with which the particular counter is to be assembled, and an upper, female mould block 12 the pressure surface 35 14 of which is complementary to the conformation or contour of the instep portion or moulding face 16 of the mould block 10. A novel and important feature of the invention resides in the position that the mould block 40 10 assumes in the moulding machine and the consequent relation of the mould block 12 thereto.

The mould block 10 may have formed thereon a base plate 17 designed to be bolted, 45 or otherwise suitably secured, to a horizontal bed on the moulding machine. The relation of the mould block 10 to the plane of its base plate 17 is of the greatest importance. The setting must be such that there can be no 50 slippage of the forward wing to be moulded, from its true relation to the previously moulded heel end of the counter. Accordingly the mould block 10 is set on its base with the plane of its heel-seat 18 at such an 55 angle to the vertical (slightly less than 45° in practice) that the inner angle or edge 20 of said heel-seat is uppermost (see Fig. 2). The instep mould face 16 is thus presented uppermost also, causing its ridge 22 which 60 defines the merging of the instep and arch-surfaces of the last (defined by the heavy shading on Fig. 1) to lie generally centrally below pressure surface 14 of the upper mould block 12 and thus form a bending ridge or 65 backbone about which the wing is shaped.

The wing is adapted to extend between the moulding faces 14 and 16 and above and on both sides of the instep ridge 22.

The partially moulded counter 24 is fitted on the heel end of the mould block 10 which accurately defines and maintains the position of the wing relative to the instep portion of said block and, because of the oblique setting of its heel-seat face, holds the wing in a substantially horizontal plane, as illustrated 75 in Fig. 3. It will be observed that the wing 26 stands away from the instep surface 16 of the male mould block although the moulded heel end of the counter is supported by the heel end of said mould block. Fig. 4 also 80 illustrates this condition, and shows more plainly the relation at this time of the wing 26 to the instep ridge 22. It will be observed that the instep ridge lies, generally, centrally below the wing 26 as it extends over the upper face of the male mould block. Now, on bringing the mould block 12 down vertically into counter wing moulding relation to the mould block 10, the female moulding face 14 will engage the two margins of the 85 wing 26, first bending them downward at either side of the instep ridge 22 and finally, when the female instep mould face 14 seats upon the male instep mould face 16, pressing and shaping the entire wing to the contour 90 of the instep as defined by these two mould faces (see Fig. 5). The preliminary ridge engagement enables the wing 26 to retain its position relative to the heel end while being shaped in accordance with the contour of 100 the instep which it overlaps. Thus a moulded wing is produced that, upon assembly of the counter on its last, will be pre-shaped to the contour of the instep of the 105 last and will require no manipulation during the lasting operation to bring it into the position requisite to maintain and perpetuate the beauty of the design of the last in the completed shoe.

Fig. 6 illustrates a wing counter 28 for 110 men's and women's shoes that is a product of the method of manufacture herein described. It will be observed that the heel-seat flange is perfectly formed and that the contour of the instep of the last at the inside shank has 115 been permanently impressed into the forward wing 26 without distortion thereof and without any change or shift from its true position relative to the heel end of the counter that must be retained for perfect shoemaking. The secret of this lies in the discovery of how to hold the wing 26 in the correct position between the mould blocks 10 and 12 during the wing moulding step of 120 the process to prevent slipping. The heel 125 end of the mould block 10 provides a support that will present and hold the wing in proper relation to the contour of the instep portion of said block that is to determine its moulded shape and, because said block is set angular- 130

ly, i. e. in such a position that its instep ridge 22 forms the backbone of the mould throughout this portion of the wing moulding face 16, the closing of the moulds will cause the 5 margins of the wing to be folded downward about this backbone and the wing will thus be held without slip throughout the moulding process in its true relation to the heel end of the counter.

10 Fig. 7 illustrates a wing counter 30 for women's pumps having its forward instep wing 26 moulded by the method of this invention. In fitting this style of counter on the mould block 10 the extra long outer side 15 is taken care of by suitably recessing the base plate 17.

When the method of manufacture as hereinbefore described is practised there results a pre-formed counter, of the type having an 20 inner wing that extends forwardly sufficiently to overlap the inside shank of the last, that can be lasted without the necessity of any change in form or position, and when sewed to the insole will permanently 25 preserve the style lines of the shoe at the inside shank that originate in the design of the last on which the shoe is built. The 30 type of counter described has the further function, when moulded throughout its entire surface in accordance with the teaching of this invention, of providing in the shoe an instep support of such contour and permanency as to give material aid to the support of weakened longitudinal arches and 35 consequent relief to those suffering from flat foot.

During the preceding description, and in the following claims, it has been convenient 40 to employ various terms denoting direction of movement, position and the like, but it is to be understood that these terms are not expressive of any characteristic features of the invention, as it is the relative arrangement of the parts alone which is of importance.

Having thus described the nature of the invention and the preferred method of practising it, it is definitely stated in its true 45 scope in the following claims.

50 What is claimed as new, is:—

1. The method of making pre-formed wing counters, for fitting the heel end and that portion of the inside shank of the last overlapped by said wing, which comprises moulding the counter by pressure directed against the sides of its heel end, and by pressure directed on the wing forward of the heel end from a direction that is oblique to the direction of the pressure for moulding the heel end.

2. The method of making counters of the type having an inner wing, which comprises moulding one portion of a wing type counter blank to fit the heel end of a last by pressure substantially in the direction of the

plane of the heel-seat of the counter, and moulding another portion of said blank comprising the wing to fit the inside shank of the last by pressure in a direction that is oblique to the plane of said heel-seat.

3. The method of making counters of the type having an inner wing that extends forwardly from the heel portion, which comprises moulding a portion of a wing type counter blank to fit the heel end of a last 70 leaving a substantially unmoulded wing at the inner side of said moulded portion, and then moulding said wing to a curved form to fit the instep contour of said last which it overlaps by downward pressure on said wing while it is held in a substantially horizontal plane.

4. The method of making counters of the type having an inner wing, which comprises moulding a counter blank to fit the heel end 75 of a last leaving a substantially unmoulded wing at the inner side, and then moulding said wing to fit the instep portion of said last which it overlaps by an engagement of both margins of said wing and a bending and shaping thereof into engagement with the surfaces at either side of the instep ridge whereby said ridge forms a centrally located 80 backbone for retaining said wing in its true position relative to the moulded heel end 85 during the wing moulding step.

5. The method of making counters of the type having an inner wing, which comprises moulding a counter blank to fit the heel end 90 of a last while said blank is held upon a heel end mould block leaving a substantially unmoulded wing at the inner side of said counter, and then moulding said wing to fit the instep of said last while said blank is held upon a mould block having an instep 95 moulding face which presents the ridge of said instep uppermost.

6. That step in the method of moulding counters having a forwardly extending inner wing adapted to overlap the instep portion 100 of the last which consists in applying moulding pressure to said wing in the direction of the ridge which demarks the instep and arch surfaces of the last.

7. The method of making counters having 115 an inner wing which overlaps the instep portion of the last, which comprises moulding the heel portion of a wing type counter blank to fit the heel end of the last, and then moulding the wing portion of said blank to 120 fit the instep portion of the last while said moulded heel end is supported upon an internal support which accurately defines and maintains the position of said wing portion.

8. The method of making counters having 125 an inner wing which overlaps the instep portion of the last, which comprises moulding one portion of a wing type counter blank between mould blocks designed to shape said portion to fit the heel end of the last leaving 130

- the wing portion substantially unmoulded, then supporting said partially moulded counter on a mould block having an instep portion that is of the same shape as the instep portion of the last, said last named mould block also having a heel end shaped to support the moulded heel end of the counter and to hold the wing portion in proper relation to the contour of that portion of the instep of the mould block that is to determine its moulded shape, and finally pressing said wing portion while so held, against said instep portion of said block, to shape it.
15. 9. The method of moulding blanks for wing type counters to a shape that will fit the contour of both the heel end of the last and that portion of the instep which is overlapped by the forwardly extending wing, which includes the steps of first moulding
- the heel portion of the blank by pressure between surfaces shaped to impress the contour of the heel end of the last therein, and thereafter moulding the wing portion of the blank forward of the moulded heel portion 25 by pressure between surfaces shaped to impress the contour of the instep portion of the last therein while maintaining the same relation of said wing portion to the moulded heel portion of the blank that the portion 30 of the instep of the last which it overlaps bears to the heel end of the last.
10. The method of moulding a counter having a wing extension which comprises first moulding the heel portion to shape and thereafter moulding the wing portion to shape while the heel portion is supported upon an internal heel-shaped support. 35

CLAYTON A. PETERSON.
